[57] CLAIM

The ornamental design for a male garment for attaching a disposable urine collecting receptacle, as shown and described.

DESCRIPTION

FIG. 1 is a front perspective view of a male garment for attaching a disposable urine collecting receptacle, showing my new design, the broken line showing is for illustrative purposes only and forms no part of the claimed design;

FIG. 2 is a front elevational view thereof;

FIG. 3 is a left side elevational view thereof, the right side elevational view being substantially a mirror image; and

FIG. 4 is a bottom plan view thereof, the top plan view being substantially a mirror image.

The rear of the article is substantially plain and unornamented. The cross-line pattern which is partially shown for ease of illustration is intended to represent a conventional fabric.

FIG. 1
